UNITED STATES PATENT OFFICE.

EDWARD GURNEY, OF TORONTO, CANADA.

DESIGN FOR A HEATING-STOVE.

SPECIFICATION forming part of Design No. 25,947, dated August 18, 1896.

Application filed September 8, 1895. Serial No. 561,352. Term of patent 7 years.

To all whom it may concern:

Be it known that I, EDWARD GURNEY, a subject of the Queen of Great Britain, residing in the city of Toronto, in the county of York, in the Province of Ontario, Canada, have invented and produced a new and original Design for Wood-Stoves, of which the following is a specification, reference being had to the accompanying drawings.

Figure 1 is a side elevation, Fig. 2 a rear view, and Fig. 3 a plan view, of the stove embodying the design.

The leading feature of my design consists in a stove of substantially oval shape, having convex sides, with a projection protruding from one of said sides. This protruding part has a flat upper face flush with the top surface of the body of the stove. The sides and bottom thereof are rounded and gradually

merged into the side of the stove. This part is of less length than the stove and projects at its widest point out beyond the vertical plane of the side thereof.

A is the body of the stove, and a' is a projection having rounded sides and a flat top a², provided with thimble B.

C is a stovepipe-thimble.

The back E' has an oval raised panel E².

F are legs which have a curved form and are connected together by the scalloped configuration shown.

I claim—

The design for stoves herein shown and described.

EDWARD GURNEY.
